UNITED STATES PATENT OFFICE

2,431,201

DRYING OF POROUS MASSES

Donald W. Ross, Washington, Pa.

Application April 21, 1944, Serial No. 532,030

3 Claims. (Cl. 34—26)

1

This invention relates to the drying of liquid-containing porous masses, and finds practical application in the drying of articles of ceramic ware, including refractories, particularly large refractory bodies (such as tank-blocks used in the side walls of glass furnaces), after they have been shaped and before they have been fired. The application for this patent consisted in a continuation in part of my application Serial No. 323,925, filed March 14, 1940, and notice is also given of Letters Patent No. 2,320,474, granted to me June 1, 1943, and of an application, Serial No. 484,547, filed by me April 26, 1943, relating to the same general subject.

In the accompanying drawings:

Figure 1 is a diagrammatic view in perspective of a tank-block within a chamber, and in condition for the practice of the invention, the wall of the chamber being broken away better to reveal the arrangement of the tank-block within; and

Figure 2 is a view in vertical section of an article formed of ceramic material and known in the industry as a glass-melting pot, and upon such article the invention may be practiced, as will be explained.

It is commonly known that, in the drying of porous material, the air first penetrates the coarser pores, and that the water continues longer in the finer pores. I have perceived another principle that expresses itself in water-filled capillaries, and upon this other principle my present invention proceeds. When a capillary is partially filled with water, menisci are formed at the ends of the column of water; if then there be a difference in temperature at the ends of the water column (having equal menisci), the cooler meniscus will exert a greater surface tension, and the column will tend to flow in the capillary in a direction from the warmer to the cooler end of the column. The tendency expresses itself in exosmosis. Surface tension varies with temperature. Hence, the control of the temperature of a relatively warm portion of the surface of a porous mass and the control of the temperature drop between that portion of the surface and remainder of the surface, together control the pull of surface tension from the warm portion of the surface to the cooler portion.

When articles of ceramic ware are taken from the molds in which they have been formed they still are burdened with water, and, before their introduction into the kilns, they have to be dried. It is usual practice to introduce the water-containing articles as they come from the molds into a drying chamber: the articles in relatively cold

2

state are brought into a relatively warm atmosphere. Under such conditions the surface-tension action that I have described tends to carry the water, not outward toward the surface, where it may evaporate, but inward; furthermore, superficial drying tends to bring about a case-hardened condition, that hinders and delays subsequent drying.

My present invention consists in controlling a water gradient from a relatively warm portion of the surface of a porous mass to the cooler portion. I accomplish this, as noted above, by controlling the heat gradient from the warmer to the cooler portion of surface; and I accomplish the control of heat gradient, in turn, by controlling the temperatures and humidities of both the warmer and cooler portions of the surface. In accomplishing this end I may, under proper conditions, let temperature and humidity at the cooler portion of the surface, vary with the weather. Alternatively, I may control either temperature or humidity, or both temperature and humidity, at the cooler portion of the surface. In any case I control automatically (and vary) the conditions at the warmer portion of the surface, so as to insure suitable heat and water gradients from the warmer to the cooler portion, as described hereinafter.

The supplying of heat may be effected in various ways, the essential thing being that a heat gradient is established and maintained that descends from the portion of the surface so heated to the free or unheated (cooler) portion. When such a heat gradient is established, the water contained in the mass will flow from the warmer portion of the surface and through the substance of the mass to the cooler portion of the surface. Such acceleration of flow is apparently due to the condition described above. That is to say, the heating of minute columns of water within the mass, so that the pull of the menisci at the heated ends is less than the pull of the menisci at the cooler ends of these minute columns, creates a tendency for the water to migrate toward the cooler surface.

Necessarily, the heating of the porous mass over a portion of its surface will, unless preventive measures are taken, induce superficial evaporation; that portion of the surface will become unduly dry; localized shrinkage will occur; and the risk of loss by cracking will be brought about. Such a condition I prevent by maintaining the humidity of the atmosphere at the heated surface sufficiently high substantially to prevent evaporation. Necessarily, as the drying of the mass

progresses, there will under such conditions be a flow of water from the heated surface into the mass, and to that extent there will be retardation of the drying operation as a whole. However, this inevitable inflow of moisture will be of relatively small magnitude, and, by a proper control of conditions as the drying operation progresses, substantially complete drying may be effected, and the procedure rendered economically valuable. As the drying progresses, the humidity over the heated portion of the surface may be lowered. Heat may be applied by radiation, by convection, or by conduction, or by space heaters, or by warm air, or by other warm substances in contact with the surface. It is possible to provide apparatus automatically to control the rate at which heat is imparted to the warmer portion of the surface according to humidity and temperature conditions over the cold portion of the surface, it being desired to effect such control in order that the rate at which moisture is driven to the cooler portion of the surface will be adequate to prevent the cooler portion of the surface from becoming dry and shrinking, with the harmful consequences known to the art.

Referring to Figure 1, a tank-block that may be understood to be moist is arranged within a chamber 2, and rests upon the floor thereof. A partition within the chamber extends in the plane *a*, *b*, *c*, *d*, and extends to the block, along the line *e*—*f*—*g*—*h*. On the two sides of this partition, by means of heating and circulation apparatus, the conditions of relative temperature and humidity that are specified may be maintained; and control apparatus may be provided, for attaining such conditions, for maintaining them, and for varying them as drying progresses.

It will be understood that conditions of relatively great humidity and relatively high temperature are to be maintained upon the near side of the partition, while conditions of relatively low humidity and relatively low temperature are to be maintained on the remote side. A fan 3 and a vent 4 may be provided, by means of which air, drawn from the outer atmosphere, is delivered through the portion of the chamber on the near side of the partition. The air so delivered is heated and moistened (if need be) so that the conditions of humidity and temperature, to which the body of the block on the near side of the partition is exposed, may be controlled and varied as the drying operation progresses. In the line of air flow from the outer atmosphere into the chamber, means may be provided for affording the desired control of humidity and temperature, and, in exemplary way, I show in Figure 1 a burner 7 and a water spray 8 for such purpose. As already indicated, the temperature of the air delivered by fan 3, will be substantially higher than the temperature of the air on the far side of the partition, and the relative humidity of this warmer air will be substantially 100%, so that practically no evaporation will occur from the portion of the block on the near side of the partition.

On the far side of the partition, the flow of air through the chamber is effected by means of an exhaust fan 6, which draws air into the chamber through an inlet duct 5.

Ordinarily, the air drawn through the chamber on the far side of the partition is untreated atmospheric air, and the desired heat gradient through the block 1 is obtained by regulating the temperature of the saturated air delivered to the chamber on the near side of the partition. In

case the natural atmospheric air in a particular region, or in a particular season, is too humid for effecting the desired evaporation of moisture from the position of the block on the far side of the partition, the air may be passed by way of a branch 50 through a refrigerating unit 9 and its humidity lowered to proper value. The humidity of the air entering the chamber may also be controlled by means of a heater 10 that is arranged 10 in a valved branch line 51 of the duct 5. Indeed, by regulation of the refrigerating and heating effects of the units 9 and 10, the desired condition of temperature, as well as humidity, may be maintained in the stream of air entering the chamber 2 on the remote side of the partition. Thus, migration of water within the body of the block may be maintained in direction from the near side toward the far side, and it will be understood that the humidity of the air on the far side of the partition may be adjusted and maintained at such degrees as to effect evaporation from the block at rates suited to the conditions of wetness of the surfaces of the block on the far side.

25 In such an article as that illustrated in Figure 2, no dividing partition is required when the moist article is brought within a drying chamber. The wall of the article may suffice to separate the inner and outer chambers. As between such 30 inner and outer chambers, the conditions of relative temperature and humidity that are specified may be established, maintained, and varied; with the effect that drying is thorough, rapid, and so carried out that the integrity of the 35 article is not endangered.

The drying of porous masses with the practice of the invention which is here described is applicable throughout a wide range of practical procedure. By observation of a thermometer and 40 psychrometer, the conditions of temperature and humidity on the cooler side of the article can be determined, and from such data the proper temperature to establish on the warmer side of the article can be ascertained. Indeed, the latter 45 temperature can be established by means of known and available automatic temperature-humidity control apparatus, a consideration of which apparatus is not essential to an understanding of this invention. In practice the temperature of 50 the cooler surface may range from below the freezing point to above the boiling point of the moisture to be removed from the mass, and the relative humidity may range from 0 to 95 per centum. In the drying of certain masses or articles the temperature of the warmer side of the 55 article need be only 1 degree higher than the cooler side, and in some cases the temperature difference must vary several degrees. In the case of relatively dry articles, temperatures as high as 60 257° F. have been maintained on the warmer side of the article, while the temperature on the cooler side was 70° F. In cases where the center of the body of the article contains a substantial quantity of moisture, the relative humidity of the air on 65 the warmer side of the article must be as high as 98 per centum, but if the article is or becomes relatively dry the relative humidity of the air on the warmer side of the article may be lower, in some cases as low as 75 per centum. The 70 quantity, temperature and humidity of air to be passed over the opposite sides of the porous article may be ascertained by a consideration of the Willis Carrier psychrometric charts, as given in Marks Engineers' Hand Book, third edition, 75 page 352. The rate of flow of moisture through

porous masses depends upon a number of independent variables, including temperature difference between the opposite sides of the mass, the kind of porous material through which the flow is effected, the thickness of the mass in which flow is promoted, and the change of pore size caused by shrinkage during the drying process. Calculations of temperature and humidity are, therefore, not given in this specification. They would involve assumptions of rates of flow for given temperature differentials between the opposite sides of the mass or article at successive time intervals throughout the operation. Suffice it to say that persons skilled in the art, and having this specification before them, may readily avail themselves of the invention.

With this specification in hand, persons skilled in the art will fully understand how to practice the invention and obtain the advantages described.

The invention will prove useful in the removal of water from other bodies than porous masses, and may be useful in the removal of other liquids than water. Within the scope of the appended claims many variations and modifications are held in contemplation.

I claim as my invention:

1. The method herein described of controlling the drying of a water-containing porous mass, which consists in passing over one portion of the surface of the mass a stream of air of humidity substantially preventative of evaporation and simultaneously passing over another portion of the surface of the mass a stream of air that is cooler and drier than that of the first named stream, and as drying progresses reducing the humidity of the air of the first named stream.

2. The method herein described of controlling the drying of a water-containing porous mass of newly formed ceramic ware, which consists in passing over one surface of the mass a stream of air of humidity substantially preventive of evaporation and simultaneously passing over the opposite surface of the mass a stream of air that is cooler and drier than that of the first named stream, and as drying progresses reducing the humidity of the air of the first-named stream.

3. The method of drying a water-containing porous mass which comprises exposing each of two surface areas of the mass to a different atmosphere, one atmosphere being a variable relatively cool evaporative atmosphere and the other being a relatively warm and substantially non-evaporative atmosphere, and controlling and varying, in accordance with variations in the temperature and humidity of the relatively cool evaporative atmosphere, the temperature and humidity effective upon the surface area of the mass exposed to the relatively warm non-evaporative atmosphere
